[57] CLAIM

The ornamental design for a necropsy board for large animals, as shown.

DESCRIPTION

FIG. 1 is a perspective view of a necropsy board for large animals embodying my new design;

FIG. 2 is a top plan view of the board;

FIG. 3 is an end view;

FIG. 4 is a side view;

FIG. 5 is a cross-sectional view taken generally along lines 5—5 of FIG. 2;

FIG. 6 is a cross-sectional view taken generally along lines 6—6 of FIG. 2;

FIG. 7 is a cross-sectional view taken generally along lines 7—7 of FIG. 2;

FIG. 8 is a cross-sectional view taken generally along lines 8—8 of FIG. 2;

FIG. 9 is a cross-sectional view taken generally along lines 9—9 of FIG. 2;

FIG. 10 is a cross-sectional view taken generally along lines 10—10 of FIG. 2; and

FIG. 11 is a bottom plan view of FIG. 2.
